UNITED STATES PATENT OFFICE.

MILLARD BUTTS, OF NEW YORK, N. Y., ASSIGNEE TO MERGENTHALER LINOTYPE COMPANY, A CORPORATION OF NEW YORK.

TYPOGRAPHICAL MACHINE.

1,000,486.

Specification of Letters Patent.

Patented June 9, 1914.

Application filed May 18, 1913. Serial No. 327,045.

To all whom it may concern:

Be it known that I, MILLARD BUTTS, a citizen of the United States, and a resident of New York, county of New York, and State of New York, have invented a new and useful Improvement in Typographical Machines, of which the following is a specification.

My invention relates to typographical machines, such as linotype machines of the general organization represented in Letters Patent of the United States, No. 436,532, to O. Mergenthaler, wherein circulating matrices are released from a magazine in the order in which their characters are to appear in print and then assembled in line together with expanding spacers, the composed line transferred to the face of a mold, the mold filled with molten metal to form a slug or linotype against the matrices which produce the type characters thereon, and the matrices thereafter elevated and returned through a distributing mechanism to the magazine from which they started. More particularly, it has reference to the parts which receive the matrices from the distributing mechanism, and its general object is to adapt such parts to receive and handle matrices of different thickness. In machines of this kind, the matrices pass from the distributing mechanism into and through a channeled entrance, which in turn delivers them to the channeled magazine, and to this end the magazine and the entrance are caused to register in such manner that their corresponding channels are practically continuous. The matrices are of varying size, depending both on the characters represented thereby and on the different styles or fonts in use, ranging for instance from a very thin one containing a punctuation mark to a very thick one representing a "head-letter". As the several fonts which are successively employed may thus contain matrices of widely different size and thickness, it has been customary to vary the relative width of the entrance channels to correspond, and this result has been generally secured by bending certain of the channel partitions, when the font is changed, the bending being sometimes performed manually and sometimes automatically.

It is the purpose of my present invention to obviate this necessity and to employ chan-

nels of permanent width, which channels are provided with guiding means adapted to engage the ears of all matrices, whether thick or thin, and consequently to guide them into correct relation to the magazine.

In the accompanying drawing I have shown my invention in preferred form and by way of example, and as applied to a linotype machine, but obviously many variations and alterations may be made therein, and further it may be adapted to other forms of typographical machines, such as typesetters, typecasters, and the like, (in other words, to handle type, etc.), without departure from its spirit. Generally speaking, I desire it to be distinctly understood that I do not limit myself to any specific form or embodiment except in so far as such limitations are specified in the claims.

Referring to the drawing: Figure 1 is a transverse vertical section through the magazine-entrance and the upper end of the magazine; Fig. 2 is a sectional view, taken substantially on the line 2—2 in Fig. 1; and Fig. 3 is a sectional view, taken substantially on the line 3—3 in Fig. 1.

The matrices X are delivered by the distributor screws A into the magazine-entrance B, from which they pass into the magazine C. The matrices are of the customary form and are provided with the projecting ears Y which engage in the side grooves C' of the magazine.

Referring to Figs. 2 and 3, it will be noted that although the bodies of the matrices vary in size from very thin to very thick, their ears Y do not vary nearly to the same extent, being of substantially uniform thickness in all the matrices, and are therefore all adapted to engage and travel in the grooves C', without regard to their body dimensions. In order that the matrices may be properly guided into the magazine channels, I provide the entrance channels near their lower ends with means to engage the matrix ears laterally, which means are preferably connected to the partitions D, and in the form shown consist of bent-over and inclined flanges D' at opposite edges thereof, so arranged and located as to encounter and guide the sides of the ears Y and direct them into the grooves C' of the magazine. It will be seen that the body of the matrices will be contained within and pass between the

2
guides D¹ irrespective of their thickness, and further that because of this construction, it will not be necessary as hitherto to alter the relative width of the entrance channels for different fonts, as the matrix ears will always be engaged and guided into correct relation to the magazine.

Although I have illustrated and described my invention in preferred form and by way 10 of example, it will be obvious that other equivalent and differently located forms of guides may be similarly employed, whether connected to the partitions or otherwise, the essential object of my invention being to effect the proper guidance of the matrices into the magazine channels irrespective of their style or thickness, and even in some instances irrespective of the correct registration of the entrance channels with those of the magazines. These and many other modifications 20 of my invention will suggest themselves to those skilled in the art and still be comprised within its scope.

Having thus described my invention, its 25 construction and mode of operation, what I claim and desire to secure by Letters Patent of the United States is as follows:

1. In a typographical machine comprising 30 matrices formed with guiding portions of substantially uniform thickness in all the matrices, the combination with a channeled magazine, and a matrix delivery entrance therefor, having a series of channels, one for each channel of the magazine, the 35 said entrance channels being formed to engage the guiding portions of the matrices and thus discharge them in the same relation to the magazine channels irrespective of their relative thicknesses.

2. In a typographical machine, the combination with a magazine and a channeled 40 matrix-delivery entrance therefor having a series of channels, one for each channel of the magazine, the said entrance being provided with guiding means located within 45 the channels to engage only the ears of the matrices so as to insure their proper delivery into the magazine channels.

3. In a typographical machine comprising 50 matrices formed with guiding portions of substantially uniform thickness in all the matrices, the combination with a channeled magazine and a matrix delivery entrance therefor provided with a series of partitions 55 dividing the same into channels to receive matrices of different thicknesses, the said partitions being formed with supplemental guiding surfaces, which irrespective of their relative thicknesses coöperate with the 60 guiding portions of the matrices and direct them from the entrance channels in the same relation to the magazine channels.

4. In a typographical machine, the combination with a channeled magazine and a 65 matrix delivery entrance therefor provided

with a series of partitions dividing the same into channels, the said partitions being formed with projecting surfaces which engage only the ears of the matrices to guide them in their passage through the entrance channels into the magazine channels.

5. In a typographical machine comprising 70 matrices formed with guiding portions of less thickness than that of the matrix body, the combination with a channeled magazine and a channeled matrix-delivery entrance therefor, the said entrance being provided with transverse deflecting shoulders located within the channels near the lower ends thereof to coöperate with the 75 matrix guiding portions so as to deflect the matrices in their passage through the entrance channels and to insure their proper delivery into the magazine channels.

6. In a typographical machine comprising 80 matrices formed with projecting ears, the combination of a channeled magazine and a matrix-delivery entrance therefor, the said entrance being provided with a series of partitions dividing the same into channels, 85 and the said partitions being formed at their lower ends with bent-over portions extending transversely across the channels to engage only the matrix ears so as to serve as guiding means for the matrices passing therethrough.

7. In a typographical machine comprising 90 matrices formed with projecting ears, the combination with a channeled magazine and a matrix-delivery entrance therefor, the said entrance being provided with a series of partitions dividing the same into channels, 95 and the said partitions being formed at the lower ends with inclined shoulders projecting into the channels to engage only the matrix ears so as to deflect the matrices in their passage therethrough and insure their proper delivery into the magazine channels.

8. In a typographical machine comprising 100 matrices formed with projecting ears of less 105 thickness than that of the matrix body, the combination of a magazine formed with a series of sets of opposing grooves to receive the matrix ears, and a matrix delivery entrance therefor having a series of channels, 110 one for each set of grooves in the magazine, the said entrance channels being provided with guiding means to engage only the matrix ears so as to direct the matrices 115 properly into the magazine grooves irrespective of their body thickness.

9. In a linotype machine comprising 120 matrices formed with guiding portions of less thickness than that of the matrix body, the combination of a channeled magazine to 125 contain the matrices, and a magazine entrance therefor having a series of channels, one for each channel of the magazine, the said entrance channels being provided with supplemental guiding means to coöperate 130

with matrix guiding portions so as to discharge the matrices therefrom in substantially the same relation irrespective of their body thickness.

5. 10. In a linotype machine comprising matrices formed with projecting ears of less thickness than that of the matrix body, the combination of a channeled magazine to contain the matrices, and a magazine entrance 20 comprising side plates and intermediate partition plates dividing the same into a series of channels, one for each channel of the magazine, the said entrance being provided 25 with supplemental guiding means located within the channels to engage only the ears of matrices in their passage therethrough.
10. 15. In a linotype machine having a series of channels, one for each channel of the magazine, the said entrance channels being provided with guiding means to engage only the matrix ears so as to discharge the matrices therefrom in substantially the same relation irrespective of their body thickness.

11. In a linotype machine comprising matrices formed with projecting ears of less

thickness than that of the matrix body, the combination of a channeled magazine to contain the matrices, and a magazine entrance comprising side plates and intermediate partition plates dividing the same into a series of channels, one for each channel of the magazine, the said entrance being provided 20 with supplemental guiding means located within the channels to engage only the ears of matrices in their passage therethrough.

In testimony whereof I hereunto set my hand this eighth day of May, 1912, in the presence of two attesting witnesses.

MILLARD BUTTS.
